US0D1001771S

(12) **United States Design Patent** (10) **Patent No.:** **US D1,001,771 S**
(45) **Date of Patent:** **** Oct. 17, 2023**

(54) **HEADPHONE**

(71) Applicant: **Razer (Asia-Pacific) Pte. Ltd.**,
Singapore (SG)

(72) Inventor: **Charles Richard Bolton**, Singapore
(SG)

(73) Assignee: **Razer (Asia-Pacific) Pte. Ltd.**,
Singapore (SG)

(**) Term: **15 Years**

(21) Appl. No.: **29/805,447**

(22) Filed: **Aug. 26, 2021**

(51) LOC (14) Cl. **14-01**

(52) U.S. Cl.

USPC **D14/206; D14/226**

(58) **Field of Classification Search**

(57) **CLAIM**

The ornamental design for a headphone, as shown and described.

DESCRIPTION

FIG. 1 is a perspective view of a first embodiment of a headphone, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

FIG. 8 is a perspective view of a second embodiment of a headphone, showing my new design;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and

FIG. 14 is a bottom plan view thereof.

FIG. 15 is a perspective view of a third embodiment of a headphone, showing my new design;

FIG. 16 is a front elevational view thereof;

FIG. 17 is a rear elevational view thereof;

FIG. 18 is a right side elevational view thereof;

FIG. 19 is a left side elevational view thereof;

FIG. 20 is a top plan view thereof; and

FIG. 21 is a bottom plan view thereof.

The broken lines immediately adjacent the shaded areas represent the bounds of the claimed design; the broken lines form no part of the claimed design.
